HINGE FOR DOORS

Thomas O. Schrader, Allentown, Pa., assignor, by
mesne assignments, to C. V. Hill & Co., Inc.,
Trenton, N. J., a corporation of New Jersey

Application March 14, 1933. Serial No. 660,742

7 Claims. (Cl. 16—80)

This invention relates to hinges for doors, and particularly to hinges of that type, designed for use in connection with refrigerator doors and other like closures, wherein spring controlled toggle lever mechanism is employed in conjunction with the hinge for swinging the door closed and maintaining it in open position when swung open to a certain degree.

More particularly the invention relates to improvements upon the hinge structure shown in United States Patent No. 1,627,329, granted to Clement V. Hill, of Trenton, New Jersey, May 3, 1927, and the object of the present invention is to provide a simplified construction of hinge embodying a novel and improved construction and arrangement of the door spring and its housing and means for tensioning the spring, and also a novel structure whereby a plurality of springs in compact form may be used in place of a single spring when desired.

With the above and other objects in view, the invention consists of the features of construction, combination and arrangement of parts, hereinafter fully described and claimed, reference being had to the accompanying drawings, in which:

Fig. 1 is a horizontal transverse section through one side of a door and its hinging jamb, showing the application of the invention, and also showing in dotted lines two open positions of the door, one an external open position such as is permitted by the hinge construction.

Fig. 2 is a view in front elevation of the parts shown in Fig. 1.

Fig. 3 is a vertical transverse section on the line 3—3 of Fig. 2.

Fig. 4 is a horizontal transverse section on line 4—4 of Fig. 3.

Figs. 5, 6 and 7 are views corresponding to Figs. 2, 3 and 4, showing a modified form of construction.

Referring now more particularly to the drawings, and especially Figs. 1 to 4, inclusive, 1 designates the hinging jamb of the doorway of a refrigerator or other enclosing structure, and 2 the door for closing said doorway.

The hinge embodying my invention comprises a relatively stationary hinge member 3 and a swinging hinge member 4. These members are adapted to be suitably secured to the jamb 1 and to the door 2, respectively. As shown, the member 3 comprises a rectangular or oblong rectangular plate having a pair of spaced ears or knuckles 5, while the member 4 is in the form of an elongated plate having at its outer end a neck portion or

projection 6 provided with eyes or knuckles 7 through which eyes or knuckles and the eyes or knuckles 5 of the hinge member 3 passes a pintle 8, whereby the hinge members are pivotally coupled.

Associated with the hinge members are toggle links or levers 9 and 10, which extend longitudinally of the hinge structure and are pivotally coupled at their inner ends, as shown at 11. The opposite or outer end of the link or lever 9 is provided with an eye or knuckle 12 pivotally connected by means of a pintle 13 with eyes or knuckles 14 on the hinge member 4, while beyond its pivoted end the major portion as well as the outer end of the link or lever 10 is bifurcated or forked, and the arms 15 of this bifurcated or forked portion are provided with bifurcated or forked extremities 16 which straddle and are pivotally connected with the knuckles 5 of the hinge member 3 by pintles 17. This pivotal connection 17 of the lever 10 with the hinge member 3 is arranged inwardly as well as in rear of the pivotal connection 8, for a purpose herein-after described.

The pivotal connection 11 between the toggle links or levers 9 and 10 is of novel construction and provides a housing for a door closing spring or springs, as well as a pivotal connection between the levers, and it also provides a means whereby the closing spring or springs may be tensioned to exert the proper degree of closing pressure on the levers. As shown, the inner end of the link or lever 9 is bifurcated or forked to provide spaced knuckles 18, and the inner end of the link or lever 10 is provided with an eye or knuckle 19 which fits between the knuckles 18. The knuckle 19 is of expanded size, or enlarged relatively to the knuckles 18, to provide an enclosing casing having a coiled door closing spring 20 which fits snugly therein. The knuckle or casing 19 is provided with a closed side 21, having an opening 22 therein to register with the openings in the eyes or knuckles 18, while the opposite side of the knuckle or casing 19 is fully open to admit of the insertion and removal of the spring and is suitably recessed to receive a plate 23 which closes such side of the casing when the parts are operably coupled together, whereby the spring is concealed from view and protected from injury. This closure plate 23 is provided with an eye or opening 24, and through the openings 22 and 24 passes a pintle pin or bolt 25 which also passes through the eyes or knuckles 18 and completes the construction of the pivotal connection between the link or lever members 9 and 10.

The spring 20 is preferably of coiled ribbon or strap type and is provided at one of its terminals with a flange or angularly bent portion 26 engaging a receiving slot 27 in the knuckle or casing 19, which slot opens at one end through the open side of said casing, while the other terminal of the spring is provided with a similar flange or angularly bent portion 28 which engages a slot or keyway 29 formed in the pintle or bolt 25, whereby the outer and inner extremities of the spring are respectively coupled to the casing 19 and the pintle 25.

This mode of mounting the spring adapts the spring to be tensioned to the proper degree for service action by rotary adjustment of the pintle or bolt 25, which is provided with an angular end portion 30 for the reception of a wrench or other suitable tool, adapting such adjustment to be readily and conveniently effected. Upon this end 20 of the bolt is fitted a ratchet collar or sleeve 31 having an angular bore corresponding to the angular end of the pintle to hold it from rotation thereon. This ratchet collar or sleeve is detachably secured to the angular end of the bolt normally against longitudinal sliding movement and displacement by means of a clamping screw or other suitable fastening 32, and the ratchet teeth of said sleeve are adapted for locking engagement with ratchet teeth 33 formed upon the adjacent knuckle 18, so that after the pintle has been adjusted to tension the spring to the desired degree the pintle may be interlocked with the inner end of the lever 10 by the ratchet connection. By this means ready and convenient adjustment of the spring to regulate its tension to any degree required may be made by means employed to form component parts of the pivotal connection between the inner ends of the links or levers 9 and 10, which parts may be readily and conveniently coupled and uncoupled in assembling or disassembling the hinge elements, so that such operations may be quickly and simply performed, with a minimum amount of time and labor, and provision made for the substitution of a new spring for an old spring or of a new pintle pin for an old one or of any other substitution for a worn or broken part to maintain the hinge always in the best serviceable condition. The end 40 of the bolt opposite its angular end is threaded to receive a retaining nut 34 secured in position thereon by a set screw or other fastening 35, by means of which it is held against casual loosening or displacement. The nut holds the closure plate 23 in position and the pintle from longitudinal displacement, and, upon the removal of this nut, the pintle may be disengaged from the links and spring to effect an uncoupling action thereof. The described construction of the knuckle 19 not only provides a casing or housing for the closing spring and a hinging knuckle, whereby the spring is concealed and protected from injury, but may also form a reservoir for holding a suitable amount of lubricant to ensure easy motion of the coils of the spring and the parts of the pivotal connection on each other.

It will be understood, of course, that in practice any suitable number of hinges embodying my invention may be employed for the proper mounting of the door 2 upon the jamb 1, and that the strength of the spring or springs of the hinges employed may be such, in proportion to the size and weight of the door 2, as to swing the door to a fully closed position in the operation of the hinges for a door closing action. By reference to Fig. 1, showing one of the hinges, it will be

seen that when the door 2 is fully closed the hinge members lie substantially in longitudinal alignment, the hinge member 10 extending at a slight angle between its pivot points, in which position of the links the links will be caused by the spring to exert through their toggle closing action a closing pressure on the door 2. When the door is swung open such relative position of the links will be maintained until, through the arc of movement of the door, the distance between the pivotal points of the outer ends of the links or levers is shortened, whereupon the toggle action will be "broken" and the links bowed and their jointed ends moved outward relative to the face of the door, whereby the pintle 25 will be operated to wind up and place the spring 20 under tension. When the door reaches an open position substantially at right angles to the face of the door frame, as indicated by the dotted position *a*, the spring will be properly tensioned for a door closing action, but the movement of the link 10 to a position in rear of the pivot 8, that is, to a position beyond center, will cause the action of the spring to be nullified and a locking connection between the hinge members and the toggle levers to be effected, whereby the door will be held while in such position from a closing action. A slight inward movement of the door beyond this position will, however, bring the link member 10 to a position in which it is no longer beyond center, whereupon the door will be free to close under the action of the closing spring. It will be observed that by reason of the forked construction of the link 10 and its mode of connection with the hinge member 3, said link member is free to swing from side to side, forwardly and rearwardly of the hinge member 3, without interference therefrom or from the door or door jamb, as a result of which the door may be opened to a still further degree, as indicated by the dotted line position *a'*, which will be desirable and advantageous under many conditions. The hinge structure described thus permits of a very wide range of opening movement of the door, thereby overcoming the objections to prior structures in which the construction and arrangement of parts is such as to cause interference and to prevent the door from having an opening movement beyond an angle of 90°.

In Figs. 5, 6 and 7 of the drawings I have shown a modification of my invention in which the forked or bifurcated inner end 18' of the link or lever 9 is made wide enough to receive a casing knuckle 19' on the lever member 10, which casing knuckle 19' and the pivot pintle or bolt 25 are of sufficiently increased size or dimensions to receive a second spring 20' arranged alongside the spring 20 and coacting therewith for a door closing action. This construction allows spring combinations of different spring strengths to be employed with advantage, and also enables two relatively weak springs to be used in place of a single strong spring, when desired, and according to manifold service requirements.

From the foregoing description, taken in connection with the drawings, the construction and mode of operation of my improved hinge and spring closure will be readily understood and it will be seen that the invention provides a device of this character which is simple, strong and durable in construction, and which is composed of a minimum number of parts compactly arranged so as to lie close to the door and door jamb, and in which the door closing spring or springs will be concealed and protected from injury or clog-

ging by dirt, dust or other foreign materials. Also it will be seen that novel means are provided for regulating the tension of the spring or springs as desired. Furthermore, it will be seen that the construction is such as to avoid the use of any interfering parts which will prevent a full opening movement of the door, the construction and arrangement of the hinge member 3 and forked lever 10 and showing a range of movement which will permit the door to be swung open to an extra degree. The construction still further provides for the ready and convenient insertion and removal of the spring or springs, and release of the door from spring tension whenever desired.

15 In the drawings hereto annexed I have illustrated my invention as applied to an offset hinge, but it will be understood that my invention is equally efficient for use in a flush hinge.

By my invention it is possible to open the refrigerator door fully wide without imposing strains upon the hinge and its parts and without liability of breaking the same.

What I claim is:—

1. In a door hinge and closer, a stationary hinge member adapted to be secured to the door jamb, a swinging hinge member pivoted to the first-named hinge member and adapted to be secured to the door, a pair of toggle levers pivotally connected at their inner ends to each other and at their outer ends to the hinge members respectively, and a closing spring acting upon said levers and enclosed by a component part of the first-named pivotal connection.

2. In a door hinge and closer, a stationary hinge member adapted to be secured to the door jamb, a swinging hinge member pivoted to the first-named hinge member and adapted to be secured to the door, a pair of toggle levers pivotally connected at their inner ends to each other and at their outer ends to the hinge members respectively, the said pivotal connection between the inner ends of the levers comprising coacting knuckles and a pintle pin uniting the same, and a coiled closing spring having its ends operatively connected respectively to the knuckle parts of said levers.

3. In a door hinge and closer, a stationary hinge member adapted to be secured to the door jamb, a swinging hinge member pivoted to the first-named hinge member and adapted to be secured to the door, a pair of toggle levers pivotally connected at their inner ends to each other and at their outer ends to the hinge members respectively, and a coiled closing spring operatively coupled to the pivotally coupled inner ends of the levers and enclosed by an element of the pivotal connection.

4. In a door hinge and closer, a stationary

hinge member adapted to be secured to the door jamb, a swinging hinge member pivoted to the first-named hinge member and adapted to be secured to the door, a pair of toggle levers pivotally connected at their inner ends to each other and at their outer ends to the hinge member respectively, the said pivotal connection between the inner ends of the levers including a spring casing member, and a coiled closing spring enclosed in said closing member and operatively connected to the said lever ends.

5. In a door hinge and closer, a pair of pivotally connected hinge members, a pair of links pivotally coupled at their inner ends to each other, one of said links being pivotally connected at its outer end to one of the hinge members, and the other of said links having a forked end straddling the other hinge member and pivoted thereto inwardly of and rearwardly beyond the pivotal connection between the hinge members, said pivotal connection between the inner ends of the link members including a spring casing, and spring closing means for coaction with the links enclosed in said casing.

6. In a door hinge, a stationary hinge member adapted to be secured to a door jamb, a movable hinge member adapted to be secured to a door and pivoted at one end to the stationary hinge member, and a pair of spring-controlled toggle lever members pivoted at its outer end to the movable hinge member and the other of said toggle lever members having a bifurcated or forked outer end straddling the stationary hinge member and pivoted thereto inwardly and in rear of the pivotal connection between the hinge members, said pivotal connection between the inner ends of the link members including a spring casing, and spring closing means for coaction with the links enclosed in said casing.

7. In a door hinge, a stationary hinge member adapted to be secured to a door jamb, a movable hinge member adapted to be secured to a door and pivoted at one end to the stationary hinge member, a pair of toggle lever members pivoted at their inner ends to each other, one of said toggle lever members being pivoted at its outer end to the movable hinge member and the other of said toggle lever members having a bifurcated or forked outer end straddling the stationary hinge member and pivoted thereto inwardly and in rear of the pivotal connection between the hinge members, and a controlling spring coupled to the jointed ends of the toggle lever members and opposing resistance to the outward movement of said members, the jointed end of one of the lever members being formed to provide a casing enclosing said spring.
